UNITED STATES PATENT OFFICE.

CHARLIE GENTRY, OF ATTALLA, ALABAMA.

COLLAPSIBLE CHICKEN-COOP.

1,133,851.

Specification of Letters Patent. Patented Mar. 30, 1915.

Application filed August 25, 1913. Serial No. 786,564.

To all whom it may concern:

Be it known that I, CHARLIE GENTRY, a citizen of the United States, residing at Attalla, in the county of Etowah and State 5 of Alabama, have invented a new and useful Collapsible Chicken-Coop; and I do hereby declare the following to be a full, clear, and exact description of the invention, such as will enable others skilled in the art 10 to which it appertains to make and use the same.

This invention relates to a new and useful improved collapsible chicken coop.

An object of the invention is to provide a 15 coop of this nature, which may be easily knocked down, or folded in a small compass for shipment, and one which comprises desirable and practical features of construction.

20 One of the features of the construction is the provision of means for not only holding the coop opened and in readiness for use, but for holding the same folded or collapsed equally as well.

25 Another feature of the invention is that the hinged sides or ends fold in such wise as to permit of the reception of a metal feed and water pan, the top of the coop, when the same is collapsed or folded, prevents upward displacement of the pan.

Another feature of the invention is the particular manner of hinging the foldable or collapsible parts.

30 In practical fields the details of construction may necessitate alterations, to which the patentee is entitled, provided the alterations fall within the scope of what is claimed.

The invention comprises further features 35 and combination of parts, as hereinafter set forth, shown in the drawings and claimed.

In the drawings:—Figure 1 is a view in perspective showing the improved foldable chicken coop open in condition for use. Fig. 45 2 is a perspective view showing the foldable coop collapsed. Fig. 3 is a sectional view on line 3—3 of Fig. 1. Fig. 4 is a sectional view on line 4—4 of Fig. 1. Fig. 5 is a sectional view on line 5—5 of Fig. 2. Fig. 6 is a perspective view of the improved coop 50 showing the sides and ends folded.

Referring more particularly to the drawings 55 1 designates the bottom of the improved coop. This bottom comprises the bottom piece 2 and the side and end flanges 3 and 4, which flanges overlap one another

at the corners of the coop, as shown at 5, there being metal corner pieces 6, to render the connections secure, as shown. These flanges rise a little above the bottom piece 2. 60 The side flanges 3 have strips 7 secured adjacent thereto, and to the bottom piece 2. The foldable sides 8 comprise the rectangular frames which consist of the bars 9 and 10 overlapping one another at the corners 65 and secured together in any suitable manner, the overlapping construction being denoted by the numeral 11. Each side 8 is provided with mesh work 12, and one of the pieces of mesh work is provided with a 70 metal frame 13, having a metal and mesh work door 14 hinged at 15, there being a suitable padlock 16 for holding the door locked. The bars 9 and 10 are braced relative to one another by the strips of metal 17. 75

The foldable end parts 19 consist of the bars 20 and 21 connected in a manner similar to the connections of the bars 9 and 10, but not particularly shown. The bars 20 and 21 are braced relative to one another by 80 the metal strips 22, and are provided with mesh work 23.

The lower edges of the sides are provided with grooves 24 receiving the rods 25, which are held in place by the staples 26. These 85 rods 25 are constructed with angular ends or portions 27, which are mounted in staples 28 of the end flanges 4. In this manner the sides are pivotally connected in place. It will be noted upon reference to Fig. 4 that 90 the sides 8 are alined above and with the strips 7.

The lower edges of the end parts are provided with grooves 29 receiving the rods 30, which are held in the grooves by the 95 staples 31. The ends of the rods 30 are mounted in recesses or bearings 31^a of the side flanges 7. In this manner the end parts are hingedly connected in place, the lower edges of the end parts engage the bottom 100 piece 2 of the coop, as shown in Fig. 3. It will be noted that the end parts first fold inwardly adjacent the bottom piece 2, as shown in Figs. 5 and 6, while the sides fold upon the end parts, as particularly shown in 105 Fig. 6.

The top 32 of the coop comprises the top piece 33 and the flanges 34 which overlap one another at the corners as shown at 35, there being metal corner pieces 36 to render 110 the connections secure. The flanges 34 extend partially down upon the outside of the

side and end parts, when the coop is in condition for use, as shown in Figs. 1, 3 and 4. However, when the coop is collapsed or folded, the top 32 covers the folded side and 5 end parts, while the flanges 34 assume positions adjacent the flanges 3 and 4.

The bars 21 of the end parts are provided with openings or bores 37, which receive the bolts 38, the heads of which are countersunk 10 in the top, as shown at 39. The lower ends of the bolts 38 have winged nuts 40 threaded thereon, to hold the top in place.

When the coop is folded as shown in Figs. 2 and 5 the same bolts 38 extend through 15 apertures of the bottom piece 2, said apertures being designated by the numeral 41, the same winged nuts 40 are received by the bolts 38; so as to hold the parts of the coop in a collapsed relation. When the coop is 20 collapsed the winged nuts 40 are countersunk in the recesses 42 of the bottom. The top is constructed with an opening 43 having an area of mesh work 44 covering the same.

25 When the side parts are folded, as shown in Fig. 6 a space 45 between the adjacent edges of the side parts 8 is formed, for the reception of the metal feed and water pan 46. When the parts are folded as shown in 30 Fig. 6 with the pan 46 in place, the top may then be placed in position as shown in Fig. 2, and in this manner displacement of the pan 46 is prevented.

It is to be understood that this improved 35 foldable or collapsible coop may be constructed of any suitable material, wood or other fiber, or metal or the like.

The inventor is well aware that foldable 40 chicken coops have been conceived and constructed prior to the present invention, therefore the patentee is not claiming the broad construction. But as will be noted 45 the inventor is particularly claiming the essential features of loosely and slidably connecting the side and end parts of the coop to the bottom of the coop, the hinged rods of

the side parts being formed with angular ends and secured by staples (which pass or arch over the angular ends) to the end flanges adjacent the side parts or side 50 flanges of the coop as specifically and definitely defined in the appended claim.

The invention having been set forth, what is claimed as new and useful is:—

A foldable chicken coop comprising a bottom having side and end flanges, the side flanges having strips arranged adjacent thereto, side and end parts, each comprising an open frame having an area of mesh work thereover and provided with corner reinforcing metal members, the side and end parts having longitudinal grooves in their lower edges, rods arranged in the grooves of the said parts, staples arching the rods and bridging the grooves to loosely and slidably connect the said parts to the rods, the rods in the grooves of the side parts having angled ends, staples arching the angled ends and connected to said end flanges for holding the rods of the side parts in place and against longitudinal movement, the rods carried by the end parts being mounted in bearings of said strips and positioned adjacent the inner faces of the end flanges, the end parts being foldable inwardly adjacent the bottom whereas the side parts are foldable on the end parts, a top member for the coop, bolts passing through the end parts and the top to hold the structure of the coop in readiness for use, said bolts when the 80 side and end parts are folded and the top covering the same, adapted to pass through the bottom adjacent the lower edges of the end parts and the end flanges and through the top to hold the structure collapsed.

In testimony whereof I have signed my name to this specification in the presence of two subscribing witnesses.

CHARLIE GENTRY.
